UNITED STATES PATENT OFFICE.

GINO PICCIONI, OF TIVOLI, ITALY.

MULTIPLE REPRODUCTION OF PATTERNS.

1,340,460.

Specification of Letters Patent. Patented May 18, 1920.

Application filed December 22, 1917. Serial No. 208,513.

To all whom it may concern:

Be it known that I, GINO PICCIONI, a subject of the King of Italy, and resident of Tivoli, Italy, have invented certain new and useful Improvements in the Multiple Reproduction of Patterns, of which the following is a specification.

My invention relates to the multiple reproduction of patterns or designs upon fabrics, the object being to correctly reproduce repeated designs or patterns upon a plurality of fabrics arranged parallel to each other at short distances apart.

An improved process and apparatus according to my invention are shown, by way of illustration, in the accompanying drawings, in which—

Figure 1 is a front view of the frame in which are held firmly pressed together in a block sheets of cardboard, on the polished and smooth edges whereof the design to be reproduced is painted, or otherwise produced.

Fig. 2 shows a transverse section of the said frame.

Fig. 3 shows a vertical section of the essential part of the machine for reproducing the designs.

Figs. 4 and 5 show one of the embroidery needles in two different operative positions.

Fig. 6 shows the apparatus partly in section used to number and measure the portion of color on each one of the edges of the sheets of cardboard.

Fig. 6^a is an enlarged view of a portion of Fig. 6 illustrating how the ribbon is impressed.

Fig. 7 is a plan view of the apparatus shown in Fig. 6.

Fig. 8 shows in elevation a modification of the apparatus used to divide off the colors and portions thereof as appearing on the edges of the sheets of cardboard.

Fig. 9 is a plan view of the apparatus shown in Fig. 8.

Fig. 10 is a section on an enlarged scale along the center line of the said apparatus.

Fig. 11 shows a numbered ribbon of a dissected design and the bobbin therefor.

Fig. 12 shows a special fabric for the reproduction of a design.

According to this invention, the picture or design to be reproduced is first dissected

by the separation of the sheets of cardboard, the edges of which sheets each have some spots of color, which according to size and tint are indicated by certain numerals. These numerals are reproduced upon the ribbons which are used for reading a pattern and are translated by aid of threads of colors corresponding in shade and in number to said indications.

After the picture has been produced in the fabrics the latter are separated one from another by means of the special cutting mechanism described farther on. Each fabric thus completed reproduces a copy of the picture with color effects equal to those of the original.

The picture to be reproduced is executed upon a smooth surface formed by the juxtaposition of sheets of cardboard, wood, metal or the like, like the leaves of a book. The sheets which thus arranged form the surface bearing the picture are numbered from the first to the last and are inclosed in a special frame in which they are firmly held so as to present an even and smooth surface.

By dividing the latter into its various units (sheets) each one of the sheets will show on its edge colored spots which are fragments of the entire picture.

Consequently on the edge of each sheet there will be found spots of color of different size and shape. Each spot of color is represented by a numeral, and also for the extent of the spot of color is provided a fixed measure as unit, which may be stated in millimeters, or fractions thereof.

Each portion of color on each sheet is compared with a scale on which are painted all the different shades of colors.

After the exact color and the extent of each spot has been ascertained the corresponding numeral is printed, by the apparatus hereinafter described, upon a ribbon which is wound upon a bobbin.

Supposing that a spot of color is a bright red or of a similar shade, a comparison is made with the aforesaid scale on which the corresponding shade of color bears a numeral, say 40. And supposing further that the spot has an extent of 5 divisions, it follows that there will be 5 points of bright red with the numeral 40. The next shade may be represented, say by the numeral 41, and supposing that it extends through 4 divisions,

there will be 4 points "41," and so forth. Upon the ribbon there will then be printed 5 times "40" and following this 4 times "41" (see Fig. 11).

5 By proceeding in the same manner for each sheet of cardboard the operator finally will obtain a ribbon or a number of ribbons upon which are printed a series of figures which represent the colors of the spots on 10 the edges of the sheets of cardboard. And these figures will evidently correspond to the colors of the colored threads of wool or other material used to reproduce the original. The ribbons are numbered and 15 kept for the purpose of reproducing copies without the original.

In order to determine the numerals corresponding to the extent and shade of color 20 of each spot on each of the sheets of cardboard, and to print these numerals upon the ribbon or ribbons referred to use is made of the apparatus, shown in Figs. 6, 6^a and 7.

The cardboard sheet —a— is placed with 25 the colored edge up vertically into a slot of the supporting frame 2. Almost touching the sheet —a—, there is on one side a band 3, bearing divisions, *e. g.*, measured by millimeters, (Fig. 7) for measuring the extent of the shades of color. On the other 30 side of the sheet —a— is provided a shift-able plate 4, bearing a scale of the colors, which are each represented by a numeral.

By shifting the plate 4 lengthwise, one 35 finds the shade of color corresponding to that upon the edge of the cardboard sheet. The starting point for the shade of color on the plate 4 and upon the cardboard sheet must register with zero on the ribbon 3 for measuring the extent of the color. After the 40 color has been ascertained on the plate 4 one will have also the number corresponding thereto, which is then printed upon the pattern ribbon 17 by means of a character shown at 5 in Figs. 6 and 6^a, in which figure the numeral 6 indicates the printing table over which the ribbon 17 passes.

The characters or types indicated at 5 are 50 fixed to the under surface of the plate 4, each shade of color bearing its particular number.

By a turn of the handle 7, a pointer 8 is brought opposite a number corresponding to the ascertained color which number is provided on the arc of a sector 9. By the turn 55 of the handle 7, the axle 12 on which the handle is mounted moves by means of a projecting bracket 13, a sector 11 so as to move the corresponding character "10" carried on the sector 11 opposite the 60 counter-pressure table 6^a for printing onto the ribbon 17 which passes over the table 6 the numeral corresponding to the ascertained color. The handle 7, is returned to its initial position by the action

of a coiled spring inclosed in a casing 16 65 while the sector 11 which bears the characters "10" is arrested and held in place by means of mutually engaging stops 14 and 15.

The return movement of the handle 7 is effected in the following manner: Secured 70 to the hub 29^a of the handle 7 is a gear 28^a with which meshes a gear 30^a carried by a shaft 31^a. On the latter is mounted also a gear 32^a with which meshes a gear 33^a carried by a spindle 34^a to which is fastened 75 the one end of the coiled spring inclosed in casing 16. The spring, with its other end fastened to the casing tends to always turn the handle 7 back to its original position.

When the handle 7 is released and turned 80 back by the coiled spring referred to it strikes against a stud 26 which under the effect of this blow moves backward the lever 27. The latter, through the link 27^a, actuates the hammer 28, whereby the number 85 is impressed upon the ribbon 17 by means of a color ribbon 17^a.

The subsequent rising of the hammer 28, causes the catch 14 to be disengaged from 90 stop 15 carried by the sector 11, which by the action of a spring inclosed in box 29 is returned to its original position, the said spring being secured with one end to the hub of said sector. The catch 14 and stop 15 are held in engagement by a spring 14^a. 95 The latter is fastened to a pivoted link 14^b which is in the path of the hammer 28. As the latter, therefore, returns to its elevated position, it trips said link thereby causing the disengagement of catch 14 from stop 15. 100

Through the backward movement of the handle 7, the ribbon 17 is at the same time moved forward, by means of the sprocket-wheel 21, which through a sprocket-chain (not shown) turns the bobbin on which the 105 ribbon winds, so that a free space on the ribbon comes in position to be printed upon.

Also the clutching apparatus, bearing the 110 sheet of cardboard is advanced to the required extent, by means of the gearing 22, 23 and thus a new point of the color spot is 115 made to register with zero on the scale 3. To prevent any accidental backward motion of the sheet of cardboard and the ribbon 17, a ratchet wheel 19 is provided and also a pawl engaging the same, the ratchet wheel being mounted on the axle 20 of the gear wheel 22.

The operator proceeds in this manner 120 with each color spot on the edge of the cardboard sheet and thus obtains a ribbon bearing consecutively the numbers corresponding to the particular color and the extent of each portion of the said color. After all the colors on the cardboard sheets have thus 125 been determined and printed on a ribbon 17, the latter which is wound upon a bobbin (Fig. 11), is used for the selection of the

colored threads used for the reproduction of the design or picture.

On the end 38 of each ribbon 17 (Fig. 11) is marked the subject of the picture, the name of the author, and any other indication which may be useful. Moreover, there is placed on the ribbon the corresponding number of the volume of cardboards —*a*— (Fig. 1) which number is followed by the numbers indicating the colors of the dissected picture. These numbers are totaled up, and the total of each sequence of like numbers, as seen in Fig. 11, is placed near the right edge of the ribbon and printed with a color different from the others and in heavier type. Near the left edge of the ribbons are printed controlling numbers in progressive order from 10 to 20, 20 to 30, etc. These controlling numbers make any possible error or mistake in the exact reproduction of the original impossible.

With the ribbons thus produced, one can without the co-operation of the apparatus afterward described reproduce any picture or design on a special background. (Fig. 12) upon which is shown a net work. The latter is divided into squares of tens, lines of different color with numbers corresponding to the lines being used. The numbers appearing upon the backing on the sides "A," "B," correspond exactly to the controlling number near the left edge of the ribbon 17. The numbers appearing on the sides "C," "D," correspond to the progressive numbers from 10 to 20, 20 to 30, etc., of the sheets of cardboard.

Thereupon, the skeins are divided in order to select the indicated threads, the shade and the number of which correspond to the aforesaid numbers printed on the ribbon or ribbons 17 and to the total of these numbers. The selected threads are then arranged upon grooved tables corresponding to the colored portions on the edges of the various cardboard sheets. In this manner one proceeds for each ribbon 17.

This process is carried out, for instance, by an arrangement of the threads selected in the manner just stated in the part of the machine shown in Fig. 3. Upon the upper bars —*c*— and the lower ones —*d*— are mounted the backings of a fabric —*f*—, in such a manner as to be well stretched, suitable intervals being provided. Upon the front side of the machine, which in this case is that on the left of Fig. 3, there are suspended the selected variously colored threads which may be arranged in wooden frames. At the same height, upon the rear side of the machine, *i. e.*, on the right of Fig. 3, there are arranged side by side in a horizontal plane —*g*— a row of needles, the number of and the distances between which corre-

spond to the numbers of and the distances 65 between the threads suspended on the front side of the machine.

One of the needles is shown in Figs. 4 and 5; it consists of a tubular part —*h*— containing a needle —*i*— provided with a hook. 70 This needle —*i*— can be moved lengthwise backward in the tubular part —*h*—. All the needles are operatively connected together so that the tubular parts can be moved simultaneously through the backings —*f*—, 75 while the needles —*i*— remain therein enclosed. (The mechanism for operating the needles is not shown in the drawing). Between the backings —*f*— are placed fixed bars —*k*— which have guides —*m*— in alignment with the said needles, the bars —*k*— themselves supporting the layers of fabric in correct position during the passage of the needles therethrough.

The needles are first pushed through the 85 fabrics —*f*— with the needles —*i*— withdrawn into the tubular parts —*h*—, the latter being pointed making a series of holes in the fabrics.

The needles —*i*—, are then caused to project from the tubular parts —*h*—, the hooks thereby being in a position to each grasp one of the suspended colored threads. All the needles are then drawn back into their tubular parts —*h*—, whereupon the latter 95 are partly moved backward. By this backward movement the colored threads are drawn through the holes previously made by the tubular parts *h* in the fabrics —*f*—.

After this first operation another row of 100 threads is suspended on the front side of the machine and all the fabrics are either raised or lowered by the thickness of a sheet of cardboard —*a*—, whereupon, in the same manner other threads are drawn by the needles through the fabrics —*f*—.

After the pattern has been completely reproduced, the various layers are separated one from another by a special system of cutters. Each frame of fabrics contains adjacent to the other the variously colored threads, which project to the required length from both sides of the fabric.

A modification is shown in Figs. 8, 9 and 10.

A rotating disk 30 supported in a standard 31, is provided on its periphery with a numbered series of divisions 32, in each of which is placed a thread having the color corresponding to that number. This disk is 120 arranged in connection with the frame 33 upon which is adjustably placed a support 34 adapted to hold the cardboard sheet —*a*—. Close thereto is fixed in an adjustable manner to the support a mechanism, 125 such as a table provided with grooves or elastic holders 35, in which there are vertically arranged the threads corresponding

to the numbers indicated at 36 by the disk, and the corresponding portions of color on the edge of the cardboard sheet —a—.

Beneath the disk 30 is placed a receptacle 5 37 in which are arranged the loose pieces of the color threads corresponding to the color determining numbers designated by the part 36 of the disk 30. The latter revolves in accordance with the said receptacle 37.

The facility afforded by the elastic holder 35 permits the operator to rapidly take in the desired order all the colors represented by the edge of a cardboard sheet to be immediately transferred to the machine for reproducing the pattern.

In order to subdivide the backgrounds or fabrics reproducing the same pattern, one proceeds as follows:

20 The entire block of backgrounds or fabrics is removed from the machine. Thereafter, by means of a suitable cutter, such as a band saw or the like, they are divided two by two. These backgrounds thus divided in pairs are then submitted to a felting operation on their two outer sides for the purpose of felting together the back part of the pattern reproduced.

30 After this the two backgrounds which are to be separated are submitted to a horizontal cutting machine. The two faces produced by this cutter will correctly reproduce the pattern.

35 By means of this process the manufacture of felted carpets becomes possible and practical, and in this manner carpets are produced which resist wear and keep the reproduced pattern intact irrespective of wear.

40 This system of felting has been found much more suitable than the system hitherto employed, which consisted in fixing the threads on the backing of the fabric by means of cementing materials.

45 The length of the pile, whatever the material of which they are formed is immaterial because the apparatus can be adapted to enable the operator to use continuous threads after the colors once have been determined and arranged according to the scale above described.

50 All the sheets of cardboard which compose the pattern are numbered to render any error impossible with numbers corresponding to those of the dividing machine. Thus one can produce bobbins, which when provided with their respective numbers according to the different colors of the threads 55 60 will enable any person whether experienced

in the art of weaving or not to reproduce a pattern without the original.

I claim as my invention:

1. The process of simultaneously reproducing in a plurality of fabrics, patterns or designs which consists in dissecting the pattern or design into very small separate fragments, each fragment bearing a color represented by a previously fixed number, successively determining the numbers corresponding to the colors of each fragment and the extent thereof, selecting the various threads corresponding in number and color to the extent and colors of the separate fragments for reproducing the same, passing said threads close one to the other in their selected successive order through the spaced fabrics arranged in stretched condition parallel to each other, then cutting the threads between each two adjacent fabrics, and finally submitting each fabric to a felting operation thereby permanently fixing on one side thereof the loose short ends of the threads exactly reproducing the original pattern. 70 75 80 85

2. In the process, as specified in claim 1, the step of preparing the pattern for reproduction which consists in forming a smooth surface by closely placing together, like the leaves of a book, a plurality of numbered single sheets of cardboard, each sheet having a thickness sufficient to enable a color to be distinguished on the exposed edge of the sheet, placing the sheets in a frame, firmly pressing them together there- 90 95 in, so as to form of the exposed edges of the various sheets a smooth even surface, and then producing on that surface the pattern or design.

3. In the process, as specified in claim 2, 100 the step of printing the fixed numbers representing a certain color in the succession in which the colors of the pattern or design appear on the exposed edges of the various cardboard sheets upon a strip or ribbon 105 adapted to be wound onto a bobbin, the extent of color on the edge of each single cardboard sheet being represented by a correspondng repetition of the same number, and then printing on the margin of said 110 strip or ribbon the total of such repeated numbers.

In testimony whereof I have hereunto signed my name to this specification in the presence of two subscribing witnesses.

GINO PICCIONI.
